(57) **CLAIM**

The ornamental design for a RF ID tag device, as shown and described.

DESCRIPTION

FIG. 1 is a front view of the RF ID tag device showing our new design;

FIG. 2 is a rear view thereof;

FIG. 3 is a left view thereof, the right side view being a mirror image thereof;

FIG. 4 is a top view thereof; and,

FIG. 5 is a bottom view thereof.

In the drawings, the broken line showing of text depicts environmental subject matter and forms no part of the claim.
